UNITED STATES PATENT OFFICE.

MICHAEL MORRIS, OF BROOKLYN, NEW YORK.

DESIGN FOR A CABINET FOR RADIO APPARATUS.

Application filed March 28, 1925. Serial No. 12,952. Term of patent 7 years.

To all whom it may concern:

Be it known that I, MICHAEL MORRIS, a citizen of the United States, residing in Brooklyn, in the county of Kings and State of New York, have invented a certain new, original, and ornamental Design for Cabinets for Radio Apparatus, of which the following is a specification.

Referring to the accompanying drawing forming a part of this specification, the figure

is a front elevation, in perspective, of a cabinet for radio apparatus, showing my new design.

I claim:

The ornamental design for a cabinet for radio apparatus, as shown.

In testimony whereof, I have hereunto set my hand.

MICHAEL MORRIS.
